UNITED STATES PATENT OFFICE.

WILLIAM HENRY WILSON, OF NEW BEDFORD, MASSACHUSETTS.

LOOM-SHUTTLE.

1,086,970.

Specification of Letters Patent.

Patented Feb. 10, 1914.

Application filed April 18, 1911. Serial No. 621,739.

To all whom it may concern:

Be it known that I, WILLIAM HENRY WILSON, a citizen of the United States, and a resident of New Bedford, in the county of 5 Bristol and State of Massachusetts, have invented a new and Improved Loom-Shuttle, of which the following is a full, clear, and exact description.

The invention relates to loom shuttles 10 such as shown and described in the application for Letters Patent of the United States, No. 987,524, granted to me March 21, 1911.

The object of the present invention is to provide a new and improved loom shuttle 15 arranged to prevent the slack of the thread and consequent breaking thereof, and to prevent the thread from accidentally passing out of the eye at the end of the shuttle at the time the shuttle advances from the shuttle 20 box toward the cloth, as at this time the thread is liable to curl up, and if such curled thread passes between the thread guide and the body of the shuttle, it is held sufficiently tight to break on further advance of the 25 shuttle. In order to accomplish the desired result the shuttle is provided with a thread-retaining device adjacent to the throat of the shuttle body, the said retaining device having members extending from opposite 30 sides and overlapping each other to permit the entrance of a thread but to prevent return movement thereof. Use is also made of a transverse thread guide provided at its outer or delivery end with a cross bar having 35 its free end extending into the body of the shuttle to prevent the thread from passing between the exterior surface of the thread guide and the wall of the opening, into which fits the thread guide.

40 A practical embodiment of the invention is represented in the accompanying drawings forming a part of this specification, in which similar characters of reference indicate corresponding parts in all the views.

45 Figure 1 is a plan view of the delivery end of the improved loom shuttle; Fig. 2 is a side elevation of the same; Fig. 3 is a cross section of the same on the line 3—3 of Fig. 1; Fig. 4 is a plan view of the delivery end of the loom shuttle, part being

in section and the thread-retaining device being removed; Fig. 5 is a sectional plan view of the delivery end of the loom shuttle, the section being on the line 5—5 of Fig. 2; Fig. 6 is a bottom plan view of the 55 thread guide; Fig. 7 is a cross section of the body of the shuttle and showing a modified form of the thread-retaining device; Fig. 8 is a cross section of another modified form of the thread-retaining device, the section being on the line 8—8 of Fig. 9; and Fig. 9 is a plan view of the same.

The body A of the shuttle is provided with the usual elongated spindle opening B in which extends the spindle C carrying the 60 bobbin D, from which unwinds the thread D' adapted to pass through a delivery eye in the side of the shuttle body A, as herein-after more full explained. In the top of the shuttle body A adjacent the delivery 65 end is a substantially vertical opening E extending about half way through the shuttle body and connected to the recess B by a throat F. The upper end of the opening E and the sides of the throat F may be beveled 70 or cut away so as to avoid sharp edges which might cut or sever the thread.

Extending transversely through the shuttle body A is a substantially cylindrical passage G of somewhat less diameter than the 80 opening E and communicating with the lower end of the latter. A slot H extends from the opening E diagonally forward to one side of the shuttle body A, and extends downwardly in depth to approximately the 85 center of the transverse passage G. A substantially horizontal slot I connects the lower or innermost portion of the slot H with the transverse passage G along approximately one half the length of the latter.

In threading the shuttle, the thread D' is dropped through the throat F, the opening E, the slot H, the slot I and is then brought into the transverse passage G so that the 95 thread extends out through one end of the latter, as plainly indicated in Fig. 2. For preventing a loop in the thread from rising or ballooning out through the slot H, use is made of a thread-retaining device ar- 100

ranged within the opening E and so constructed as to facilitate the entrance of the thread but to prevent its return movement. The thread-retaining device may be of various forms, as indicated in Figs. 1, 3, 7, 8 and 9. The thread-retaining means shown in Figs. 1 and 3, consist essentially of a bottom plate J from which rise the sides J', J² terminating in top members J³, J⁴ 5 extending inwardly and overlapping each other, sufficient space being had between the members for the passage of the thread D' between the said members J³, J⁴ into the thread-retaining device. The front edges of 10 the top members J³, J⁴ are slightly beveled, as plainly indicated in Fig. 1, and the rear portions of the said top members J³, J⁴ do not overlap adjacent the inner end of the slot H, so that the thread 15 D' can readily pass between the members J³, J⁴ and into the slot H when threading the shuttle. A transversely-extending pin K passes through the shuttle body A and through the sides J', J² of the 20 thread-retaining device, the pin K extending over the bottom plate J so as to normally hold the thread-retaining device in position in the opening E with the bottom plate J resting on the bottom of the said 25 opening.

In the modified form of the retaining device shown in Fig. 7, use is made of two pins L and L', extending vertically in the opening E and passing into recesses formed 30 in the body A, to support the pins in position on the body A. The upper ends of the pins L and L' are provided with top members L², L³, which overlap each other, and are spaced apart for the passage of the 35 thread D', similar to the top plates J³, J⁴ above described. A depending arm L⁴ is attached to the pin L' immediately below the top member L³, and the forward edge of the said arm L⁴ is provided with a cross 40 bar L⁵, extending close to the other pin L so as to form a guide for the thread D'.

In the modified form of the retaining device shown in Figs. 8 and 9, use is made of a bottom plate N, from which rise the sides 50 N', N² terminating at the top in overlapping top members N³, N⁴, of which the member N⁴ is provided at its forward end with a projecting tongue N⁵ passing through an opening N⁶ in the side N' to guide the 55 thread into the retaining device, that is, under the top member N⁴. The top member N⁴ is also provided at its outer edge with an outwardly and downwardly curved flange N⁷ for engagement with the side of the shuttle body A to assist in holding the retaining device in place on the shuttle 60 body.

It is understood that by having the overlapping top members J³, J⁴, or L², L³, or 65 N³, N⁴ the thread D' is prevented from ris-

ing vertically out of the retaining device and the slot H, but the thread can be readily passed into said retaining device and slot H as before explained.

Within the transverse passage G is mounted a guiding device O, preferably in the form of a tube or a barrel, fitting closely within the passage G and removable lengthwise therefrom. The guiding device is preferably formed from a single piece of sheet metal so cut and stamped as to form a top opening O' from which leads a side opening O² into a transversely-extending bottom slot O³ to permit the thread to pass from the slot I into the tube and out of the same at one end thereof. Across the exit end of the guiding device O extends a cross bar O⁴ reaching beyond the wall of the opening G and terminating at its free end in a lug or point O⁵ driven into and embedded in the side of the shuttle body A, 70 so that the thread D', passing through the exit end of the guiding device O and curling up at the time the shuttle advances from the shuttle box toward the cloth, is 75 prevented from passing between the exterior surface of the tubular guiding device O and the wall of the opening G, and hence the thread is not liable to be held sufficiently 80 tight to break on the further advance of 85 the shuttle.

It is understood that in threading the shuttle it is merely necessary to drop the thread through the slot H, draw it back through the slot I, the thread in doing so 90 automatically slipping between the top members J³, J⁴ of the retaining device, the thread finally passing from the slot I into the tubular thread guide O and out of the exit end thereof over the cross bar O⁴. 95 The thread cannot become unthreaded and the thread cannot become accidentally displaced or caught between the tubular thread guide O and the wall of the opening E, and hence the shuttle does not fail to operate 100 properly.

Having thus described my invention, I claim as new and desire to secure by Letters Patent:

A loom shuttle having a body provided 115 with a transverse opening, and a tubular thread guide fitting into the said opening and provided with a longitudinal slot, and with a cross bar extending across the outside of its exit end, said cross bar being in a 120 straight line below the axis of said thread guide and extending across and completely closing the respective end of the said slot, the said cross bar having its free end provided with an angular extremity at a point 125 beyond the side of the thread guide, and bent inwardly in a direction parallel to the axis of the thread guide, said bent extremity being adapted to be driven into the surface of the shuttle body in a direction 130

parallel to the axis of its transverse opening whereby the said cross bar may be
pressed tightly against the exterior surface
of the shuttle body adjacent its opening and
thus prevent the thread from becoming
5 caught and broken.

In testimony whereof I have signed my

name to this specification in the presence of
two subscribing witnesses.

WILLIAM HENRY WILSON.
